Samuel L. McNair, Whitman, Mass., assignor to Standard Products Corporation, Whitman, Mass., a corporation of Massachusetts

Application December 11, 1952, Serial No. 22,625

Term of patent 14 years

(Cl. D83—1)

To all whom it may concern:

Be it known that I, Samuel L. McNair, a citizen of the United States, residing at Whitman, in the county of Plymouth, in the Commonwealth of Massachusetts, have invented a new, original, and ornamental Design for an Electric Foot Vibrator for Therapeutic Use or Similar Article, of which the following is a specification, reference being had to the accompanying drawing, forming a part thereof, in which:

Figure 1 is a top plan view, Figure 2 is a side elevational view, and Figure 3 is a perspective

view of an electric foot vibrator for therapeutic use embodying my new design.

I claim:

The ornamental design for an electric foot vibrator for therapeutic use or similar article, substantially as shown.

SAMUEL L. MCNAIR.
